UNITED STATES PATENT OFFICE.

ALBERT SCHNEIDER, OF PORTLAND, OREGON.

VENTILATING DEVICE.

Application filed June 2, 1924. Serial No. 717,441.

To all whom it may concern:

Be it known that I, ALBERT SCHNEIDER, a citizen of the United States of America, residing at Portland, in the county of Multnomah and State of Oregon, have invented certain new and useful Improvements in Ventilating Devices, of which the following is a specification.

This invention relates to improvements in 10 ventilating systems and has particular reference to a system for ventilating railroad cars in which passengers are to be carried, and refers to the same subject matter as that contained in applicant's abandoned application, Serial Number 513,257, of November 7th, 1921.

The principal object is to provide means whereby fresh air may be caused to circulate through the car, and to further provide 20 means for regulating the air to be circulated in accordance with the wishes of the occupant adjacent the ventilator.

A still further object is to provide means whereby all foreign substances will be filtered from the air, thereby eliminating many of the disadvantages which are common in train ventilation, such as cinders and insects.

Another object is to produce a device of 30 this character which is simple in construction, cheap to manufacture and one which may be applied to standard cars of all types without materially altering the construction of the cars, or without weakening 35 the frame thereof.

Other objects and advantages will be apparent during the course of the following description.

In the accompanying drawings forming 40 a part of this specification and in which like numerals are employed to designate like parts throughout the same,

Fig. 1 is a fragmentary view of a Pullman car having my device applied thereto and shown partly in cross section,

Fig. 2 is a vertical cross section of a car having my ventilating system applied thereto.

Fig. 3 is a perspective view showing the 50 preferred form of intake casting,

Fig. 4 is a detail view showing the intake casting installed in a car and shown in cross section,

Figs. 5 and 6 are modified forms of the 55 intake casting shown in cross section,

Fig. 7 is a perspective view showing the

arrangement of the filtering and draft controlling means.

In the accompanying drawings wherein for the purpose of illustration is shown a 60 preferred embodiment of my invention, the numeral 5 designates a railroad car as a whole to which my device is to be applied. The device consists primarily of a casting having a portion 6 which consists of a substantially rectangular portion forming a chamber 7 within which a plurality of baffles 8, 9, 11, and 12 are positioned. These baffles slant downwardly and inwardly, as best shown in Fig. 4. 70

An intake port 13 is formed in the bottom of the chamber, while an outlet port 14 is formed adjacent the upper extremity of the chamber, which other port is adapted to discharge air into a ventilating pipe 16. This 75 pipe extends through the walls of the car 5 and terminates at a point flush with the inner wall and slightly below the window casting.

It is of course obvious that the device 80 might be placed anywhere in the car without departing from the spirit of the invention.

A flange 17 is formed upon the casting through the medium of which flange the 85 device as a whole is secured to the exterior wall of the car 5.

In the modified forms shown in Figs. 5 and 6 the construction is identical, except that in Fig. 5 the pipe 16 is an independent 90 casting, and in Fig. 6 the pipe 16 terminates at a point flush with the interior of the car wall instead of projecting into the car a short distance as shown in Fig. 4.

A filter constructed in accordance with 95 Fig. 7 is employed with the device.

It will be noted that the filter consists of a frame 27 which is adapted to hold a screen 28 against which a filter 29 is placed. This screen and filter are in turn held in the 100 frame 27 by a plate 31 having a sliding shutter 32, which shutter enables the passenger to regulate the amount of air drawn through the device.

In order to induce circulation and to make 105 my system complete I provide an air outlet 33 adjacent the end of the upper portion of the car, within which air outlet I place an exhaust fan 34 which is adapted to be driven by an electric motor from the electric system of the car. 110

It is of course understood that the fan

located in the air outlet at the rear of the car is the only one in motion unless the car is standing still, in which event the fan located at each end of the car may be driven 5 if desired. In Fig. 2 it will be noted that I have placed the ventilating device in such a position that fresh air will be caused to enter the upper berths of a car as well as the lower, and I have further provided openings 10 36 in the berth cover so that the air can freely circulate through the bedding and through the car.

It will thus be seen that I have provided 15 a very simple and efficient means for properly ventilating the interior of passenger coaches.

It is to be understood that the form of my invention herewith shown and described is to be taken as a preferred example of 20 the same and that various changes in the shape, size and arrangement of parts may be resorted to without departing from the

spirit of the invention or the scope of the subjoined claim.

Having thus described my invention, I 25 claim:—

In a train ventilating device, a casting adapted to be secured to the outer wall of a car, a pipe extending through the wall in said car and communicating with said casting, said casting having an inlet port formed in the bottom thereof, a plurality of downwardly and inwardly inclined baffles positioned in said casting, means for filtering the air passing through said device, said 35 means comprising a screen, a filter pad in contact with said screen, means for holding said screen and said pad to said device, and means for regulating the rate of flow of air through said device, for the purpose 40 specified.

In testimony whereof I affix my signature.

ALBERT SCHNEIDER.
